UNITED STATES PATENT OFFICE.

REESE E. WEAVER, OF LOS ANGELES, CALIFORNIA, ASSIGNOR OF ONE-HALF TO FRANK M. WEAVER, OF LOS ANGELES, CALIFORNIA.

GAS BURNER.

Application filed June 22, 1922. Serial No. 570,189.

To all whom it may concern:

Be it known that I, REESE ELBERT WEAVER, a citizen of the United States, residing at Los Angeles, in the county of Los Angeles 5 and State of California, have invented new and useful Improvements in Gas Burners, of which the following is a specification.

This invention relates to burners and has for its object to provide a burner readily 10 adaptable for the burning of either liquid fuel or gaseous fuel. Another object is to provide a gas burner having means for regulating the mixture of gas and air. Another object is to provide a burner having means 15 for preventing sudden drafts of air from passing into the mixing chamber with such velocity as to extinguish the flame of combustion.

Other objects will be made manifest in the 20 following specification of an embodiment of the invention illustrated in the accompanying drawings, in which:

Figure 1 is a central, longitudinal section of the improved burner.

Fig. 2 is an end elevation of the regulating cap.

Fig. 3 is a side elevation of the cap.

The preferred embodiment of the invention consists of a substantial body or shell 30 2, which may be of any suitable material and dimensions and is preferably of cylindrical form. The rear end of the body is provided with a flange 3, to which is attached, as by threads 4 a nipple or burner 35 tip 5, the rear end of which is provided with a gas outlet 6.

The forward end of the burner shell 2 has a transverse wall or head 7, with a series 40 of air inlets 8. Threaded in the head 7 is a gas pipe 10, which projects through the shell 2, well into the burner nipple 5, so that gas discharging from the gas pipe 10 is mixed with the air in the nipple 5 to form a good combustible mixture at the outlet of 45 the tip.

The pipe 10 is shown as connected to a fitting 11, to one side of which is attached an oil supply pipe 12 and to the opposite side of which fitting there is attached a gas 50 supply pipe 13. The pipes 12 and 13 are provided with suitable valves 14 for cutting off the flow of fluid to the burner pipe 10.

For the purpose of preventing the sudden inflow of air through the air ports 8 with 55 such velocity as to put out the flame I have

provided a guard or shield over the inlet head 7 of the shell. Such shield is here shown as in the form of a cap 15 in the form of a cylinder having a flange 16 slidably fitting the shell so that the cap can be turned 60 on the threaded part of the gas pipe 10 to and from the air inlets 8. The cap 15 has a series of air inlet ports 17 arranged in its cylindrical portion, which overlaps the shell 2. Therefore, air passing in through the 65 ports 17 must traverse a circuitous path in reaching the air ports 8. This, it will be seen, prevents a strong indraft into the burner shell.

The cap 15 further provides for the regulation of air flowing into the air ports by virtue of its adjustment toward and from the ports.

The present burner is adapted for the burning of gas fuel from the pipe 13, and it 75 is also adapted for the burning of oil fuel from the pipe 12. In the latter case the gas pipe valve is closed and the oil pipe valve is opened.

For atomizing the oil means are provided 80 for admitting a gaseous fluid under pressure into the shell 2. Such means comprises, for instance, a steam pipe 18, having a valve 19, the pipe being threaded into the side wall of the shell 2. Therefore, when oil is turned 85 into the fuel pipe 10, it will discharge from the end thereof into the mixing nipple 5 and steam will be turned into the shell from the steam pipe 18 and the steam and oil will be intermixed in the nipple 5 and discharged 90 as a readily combustible mixture at the tip aperture 6.

To facilitate adjustment of the cap 15 it may be provided with suitable purchase 95 means as radial lugs 15'.

Various modifications may be resorted to within the scope of the claims.

What is claimed is:

1. A burner provided with a mixing chamber having a nipple projecting therefrom, a fuel pipe extending into the mixing chamber nipple, means for supplying fuel to said pipe, an air regulating means arranged at one end of the chamber and constructed and disposed so as to provide a circuitous course for the admission of air to the mixing chamber and to prevent inrush of air and the extinction of the flame. 105

2. A burner provided with a mixing chamber, a fuel pipe extending into the mix- 110

ing chamber, means for supplying fuel to said pipe, an air regulating means arranged at one end of the chamber and constructed and disposed so as to provide for the admission of air to the mixing chamber and to prevent inrush of air and the extinction of the flame, the said means including a per-

forated end head for the shell and a shield arranged to form a deflector for air currents and having a perforated sleeve portion adjustable on and spaced from the chamber. 10

In testimony whereof I have signed my name to this specification.

REESE E. WEAVER.
